US00D590021S

(12) United States Design Patent
Hughes

(10) Patent No.: US D590,021 S
(45) Date of Patent: * Apr. 7, 2009

(54) CARD FILE

(75) Inventor: William Scott Hughes, Chicago, IL
(US)

(73) Assignee: Sanford, L.P., Oak Brook, IL (US)

() Term: 14 Years

(21) Appl. No.: 29/296,836

(22) Filed: Oct. 29, 2007

(51) LOC (9) Cl. 19-02

(52) U.S. Cl. D19/76

(58) Field of Classification Search D19/65, D19/90, 92, 95, 99, 76, 89, 75, 78, 86, 91, D19/100; 40/371, 372, 373, 374, 375, 377, 40/378; 211/10, 11, 45, 50, 51, 53, 58, 163, 211/164; 312/183, 185, 188, 189, 193, 193.4

See application file for complete search history.

(57) CLAIM

The ornamental design for a card file, as shown and described.

DESCRIPTION

FIG. 1 is a perspective view showing my new design for a card file;

FIG. 2 is a right side view of the card file of FIG. 1; the opposite side view being a mirror image thereof;

FIG. 3 is a front view of the card file of FIG. 1;

FIG. 4 is a rear view of the card file of FIG. 1;

FIG. 5 is a top plan view of the card file of FIG. 1;

FIG. 6 is a bottom plan view of the card file of FIG. 1;

FIG. 7 is a perspective view of the card file of FIG. 1 in an alternate position;

FIG. 8 is a right side view of the card file of FIG. 1; the opposite side view being a mirror image thereof;

FIG. 9 is a front view of the card file of FIG. 1;

FIG. 10 is a rear view of the card file of FIG. 1;

FIG. 11 is a bottom plan view of the card file of FIG. 1; and, FIG. 12 is a top plan view of the card file of FIG. 1.

The dashed lines shown in FIGS. 1–12 illustrate environmental matter and form no part of the claimed design.
